FRED H. CORTHELL, OF CHICAGO, ILLINOIS, ASSIGNOR TO EDWARD R. HILLS, OF CHICAGO, ILLINOIS.

CHRONOMETER-MOVEMENT.

1,164,703.

Specification of Letters Patent. Patented Dec. 21, 1915.

Application filed April 14, 1915. Serial No. 21,235.

To all whom it may concern:

Be it known that I, FRED H. CORTHELL, a citizen of the United States, residing at Chicago, in the county of Cook and State of Illinois, have invented certain new and useful Improvements in Chronometer-Movements, of which the following is a specification.

This invention relates to improvements in clock and watch movements, and has for its principal object, as related to clock movements, to make feasible and practicable the employment of a balance wheel-controlled escapement in clocks employing weight or powerful spring motors such, for instance, as time recording clocks, in lieu of the pendulum-controlled escapement ordinarily used in such clocks.

As regards watch movements, the invention is designed to permit the employment of much lighter balance wheel escapements than would otherwise be necessary with a main spring of a given power.

The difficulty hitherto experienced in the effort to substitute a balance wheel escapement for a pendulum escapement in clock movements employing powerful springs or weights has been to so control the excess power transmitted from the motor through the gear train to the escapement mechanism that the latter will not overbank and fail to perform its proper function as a time measurer. As the ratios of the gears and pinions in standard clock and watch movements are constant, it has heretofore been necessary, when employing a balance wheel escapement, to carefully guard against the use of a motor that is too powerful for the escapement to control. Where pendulum-controlled escapements are used it is, of course, not necessary to so carefully regulate the power of the motor to the retarding strength of the escapement; but in a great many instances it would be highly desirable, if practicable, to substitute a balance wheel escapement for a pendulum escapement in chronometers where a pendulum escapement is necessary to properly control excess power in the motor.

By means of my present invention I have solved this difficulty, and have produced an improvement by the use of which a balance wheel escapement is entirely practicable in

clocks at present requiring pendulum escapements, and by the use of which the balance wheel escapement of watch movements may be made lighter than at present required with a main spring of a given power. The means by which the purposes of my present invention are effectuated and the mechanical embodiment of the invention itself are very simple, comprising, as the essential feature, a balanced power-absorbing weight that is applied to one of the arbors of the chronometer movement, preferably the escape wheel arbor, and, by exerting a retarding or dragging effect upon the intermittent movements of the gear train serves to control or hold in check excess power of the motor transmitted through the gear train of the movement to the escapement and thus prevent overbanking of the latter. In its simplest form this weight comprises a metal disk centrally mounted on the arbor or on the pinion carried by the latter, said disk being of suitable diameter and weight to effect the desired result in relation to the power of the motor. Where a very nice and exact regulation of the power-absorbing weight may be desired, the latter may be so constructed as to be variable or adjustable in its effect by making diametrically opposed portions thereof adjustable radially toward and from the center or axis.

The invention, its mode of operation, and the benefits and advantages attending the same will all be readily understood when considered in connection with the accompanying drawing in which I have illustrated practical embodiments and applications thereof, and in which—

Figure 1 is a longitudinal section through a chronometer escapement mechanism, its support, and the fourth arbor of the gear train; Fig. 2 is a similar view of the lower portion of Fig. 1, showing the power-absorbing weight, suitably proportioned, applied to the fourth arbor instead of to the escapement wheel arbor as in Fig. 1; Fig. 3 is an elevation of a variable or adjustable power-absorbing weight which may be employed if desired in lieu of separate weights of varying effect in situations requiring different weights.

Referring to the drawings, 10 designates one of the plates of a clock movement, and

11 another plate secured thereto and to which the escapement is attached.

12 is the escapement bridge secured to the plate 11 by screws 13.

5 14 is the balance wheel bridge secured to the plate 11 by screws 15, and 16 is the pallet bridge secured to the plate 11 by screws 17.

18 designates what is ordinarily known as the fourth pinion staff or arbor of the clock train, and 19 is the fourth pinion fast on the arbor 18.

20 designates the fourth wheel which meshes with and drives the escape pinion 21, this latter being fast on or integral with the escapement arbor 22. On the forward end of the escapement arbor 22 is the escapement wheel 23 that is controlled by the pallet 24 mounted on the pallet arbor 25.

20 The pallet is connected in the usual manner with the balance staff 26 carrying the balance wheel 27.

The parts as thus far described are or may be all as usual and well known in balance escapements of clocks and watches. In the instances shown, however, it may be noted that the escape, pallet and balance staffs or arbors are mounted in jeweled bearings, as is quite common in watch movements; my present improvement making feasible and practicable the application of jeweled escapements to clocks irrespective of the size of the latter and the power of the spring or weight motor employed.

35 Turning now to that feature wherein my present improvement resides, 28 designates a weight, herein shown as taking the form of a solid metal disk, that is applied to the escape wheel arbor 22, being herein shown
40 as formed with a hub 28' fitted over an enlarged portion of the arbor forming a lateral extension of the escapement pinion 21 and secured thereto by a set-screw 29 extending through the hub 28'. The weight
45 28 being in the form of a solid metal disk of uniform thickness and density centrally mounted on and with respect to the axis of the escape wheel staff or arbor, absorbs a part of the power of the main spring or
50 other motor to the extent of such power required to overcome the inertia of the weight at each intermittent impulse transmitted to the escape wheel arbor through the gear train. Said weight, by thus absorbing the
55 excess power transmitted to the escape wheel arbor, prevents the latter from imparting such a strong impulse to the escape wheel as would overcome the regulating effect of the balance wheel and cause the es-
60 capement mechanism to overbank. The momentum of the weight 28 is, of course, at each impulse checked by the dogging pawl of the pallet without injury to the parts, so that at each forward impulse imparted to
65 the escape pinion 21 and its staff 22, the in-

ertia of the weight has to be overcome before any movement can occur; and the overcoming of such inertia of the weight absorbs the excess of the power which would otherwise be transmitted to the escape wheel, with 70 the consequences above noted.

The power-absorbing weight need not necessarily be applied to the escape wheel arbor, but may be applied elsewhere in the gear train as indicated in Fig. 2 where 28^a 75 indicates a weight in the form of a disk mounted on and secured to the fourth pinion staff or arbor 18. Where the weight is thus applied it is necessarily of considerably greater size in order to have the required power-absorbing and regulating effect, so that the most practical place for the application of this power-absorbing weight is on the escape wheel arbor, as shown in Fig. 1. 80

In the practical use of the invention, the power-absorbing disk 28 may be made in a variety of sizes, so that a given chronometer movement may be equipped with a weight giving the right effect by experimenting with different sizes until the proper or correct weight for the movement is ascertained. As an alternative of this, however, the weight may be made variable or adjustable as to its effect by so constructing it that diametrically opposed portions thereof may be adjusted radially toward and from the axis of the weight so as to vary the inertia effect of the latter according to the amount of excess power required to be absorbed. In Fig. 3 I have illustrated a single embodiment of such a variable power-absorbing member, wherein 30 designates a disk adapted to be secured upon the escapement or other arbor of the movement in the manner already described, and 31 designates each of a pair of arms formed with weighted outer ends or bobs 32 and laterally extending inner portions 33 that are secured to the disk 30 by clamp screws 34. These arms are connected for simultaneous inward and outward movement of their outer ends by a link 35 pivoted at 36 to the end of one of the arms and at 37 to the elbow of the other. By loosening the clamp screws 34 and swinging the arms to the dotted line positions shown, the weighted ends or bobs 32 are simultaneously and equally adjusted a slightly greater distance away from the axis, so that a correspondingly greater amount of excess power in the motor is required to overcome the inertia. Obviously, many other methods of effecting radial adjustment of portions of the weight might be employed.

The improvement represented by my present invention finds its chief utility in 125 permitting the use of balance escapements, jeweled if desired, on clock movements employing comparatively powerful motors, where the use of an ordinary balance escape-
ment would be utterly impracticable because 130

incapable of withstanding and operating properly under the excessive power transmitted thereto from the motor.

I claim:

- 5 1. In a chronometer movement, the combination with one of the arbors of the movement, of a power-absorbing weight applied to said arbor and serving to control excess power transmitted through the gear train of the movement to the escapement and prevent overbanking of the latter.
- 10 2. In a chronometer movement, the combination with the escape wheel arbor, of a power-absorbing weight applied to said arbor and serving to control excess power
- 15

transmitted through the gear train of the movement to the escapement and prevent overbanking of the latter.

3. In a chronometer movement, the combination with one of the arbors of the movement, of a balanced power-absorbing weight applied to said arbor and serving to control excess power transmitted through the gear train of the movement to the escapement and prevent overbanking of the latter, said weight having diametrically opposed portions thereof adjustable radially toward and from the axis of said arbor.

FRED H. CORTHELL.
